Fig. 13.

This technical drawing illustrates a mechanical assembly, likely a saw or similar cutting device. The assembly includes a central vertical shaft (168) with a pulley (167) at the top. A horizontal frame (166) is attached to the shaft. A circular component (134) is mounted on the shaft, and a circular base (169) is positioned below it. A large, serrated wheel (148) is attached to the base (169). A vertical rod (153) is connected to the base (169). The assembly is supported by a base plate (129). The drawing also shows a lower section with a triangular base (160a) and a vertical support (161) with a circular slot (159). The drawing is annotated with various numbers: 120, 168, 133, 135, 136, 138, 137, 139, 166, 167, 130, 131, 148, 169, 153, 129, 189, 161, 159, 160a, and 160.

UNITED STATES PATENT OFFICE.

ALBERT E. MASPONS, OF PHILADELPHIA, PENNSYLVANIA.

AUTOMATIC WRAPPING MACHINE.

Application filed March 30, 1921. Serial No. 456,861.

To all whom it may concern:

Be it known that I, ALBERT E. MASPONS, a citizen of the United States, residing in the city and county of Philadelphia, State of Pennsylvania, have invented new and useful Improvements in Automatic Wrapping Machines, of which the following is a specification.

My invention relates to cigar wrapping machines and mechanism. I aim to provide for rapidly applying protective wrappings to finished cigars, and for completely covering the cigars and effectively sealing them in the wrappers, so that the cigars shall be protected against soiling, contamination, deterioration, or other injury, whether by atmospheric influences, by handling, or in other ways. I aim to accomplish the entire wrapping and sealing by a completely automatic and continuous operation or series of operations, without the necessity for manual intervention at any stage, from beginning to end.

For the purposes of my invention, I have devised a method of wrapping and sealing the cigars, especially in metal foil, by a series of novel steps or operations. The order of these steps or operations admits of some variation; and in some cases some of the steps hereinafter described may even be omitted. The mechanisms and devices which I have evolved for carrying out the wrapping and accessory operations in proper correlation are themselves new and useful, both individually, and in other combinations and sub-combinations besides those here shown and described.

In the completely automatic machine embodying my invention, which I shall herein-after describe, the unwrapped cigars may be deposited in a receiving hopper, whence they are fed and delivered to the primary wrapping and sealing mechanisms. By these mechanisms, the wrappers are fed in, a sealing agent is applied to them, and they are initially rolled about the cigars. The initially wrapped cigars are then received by suitable transfer, carrying and holding mechanism, and are thereby carried and presented, step by step, to other wrapping mechanisms and devices at successive stations; and the wrapping and sealing are thus perfected and finished in a plurality of successive operations.

In the machine here illustrated and described, the perfecting mechanisms include

devices for initially creasing, pressing down and shaping the wrapping material about the ends of the cigars; devices for gathering or compacting and smoothing the extreme ends of the wrappers and bringing them to a closer fit at the extreme ends or tips of the cigars; devices for further pressing or adjusting the wrappers to a snug conformity to the surfaces or contour of the cigars, especially on the tapered ends, where they have previously been creased and initially folded or pressed down; and devices for trimming off superfluous wrapping material at the ends of the cigars and for finally compacting and smoothing the adjacent portions of the wrappers and finally bringing them to a close fit. These "perfecting" devices are provided and arranged to operate on both ends of an initially wrapped cigar concurrently, as the cigar is held at its middle and successively presented to them by the holding and carrying mechanism. Moreover, the various parts and devices of the machine can be adjusted as may be required to enable the machine to operate to the best advantage on cigars of different types and sizes.

Other advantages and features of my invention will appear from the description hereinafter of one of various forms my invention may take.

In the accompanying drawings, which are merely a preferred form of embodiment of the invention:

Fig. 1 is an elevational view, partly in section, as indicated by line I in Fig. 17, illustrating a machine constructed in accordance with this invention.

Fig. 2 is a corresponding elevation of the hopper and chute mechanism by means of which the cigars are fed into the machine, on an enlarged scale.

Fig. 3 is a view at right angles to Fig. 2, showing another side of the hopper and chute mechanism.

Fig. 21 is an enlarged detail view illustrating the operating means for the gripper device.

50 Fig. 22 is an enlarged detail side view of one of the grippers.

Fig. 23 is a top plan view of the structure shown in Fig. 22.

Fig. 24 is a transverse sectional view taken 55 at the plane of line XXIV in Fig. 22.

Fig. 25 is a transverse sectional view taken at the plane of line XXV in Fig. 22.

Fig. 26 is an enlarged longitudinal sectional view illustrating the construction of 60 the preliminary creasing device.

Fig. 27 is a view similar to Fig. 26, but at right angles thereto.

Fig. 28 is an end elevation of the device shown in Figs. 26 and 27.

65 Fig. 29 is a transverse sectional view taken

substantially at the plane of lines XXIX in Figs. 26 and 27.

Fig. 30 is an enlarged fragmentary detail view illustrating the construction and operation of the portions of the creasing device which directly engage the cigar.

70 Fig. 31 is an enlarged longitudinal sectional view illustrating one of the devices which may be employed for gathering or compacting and smoothing the end portions 75 of the wrapping material.

Fig. 32 is a plan view of a portion of the device shown in Fig. 31.

Fig. 33 is an end view of the gripping jaws of said device.

80 Fig. 34 is an enlarged detail view illustrating the kneading devices for kneading down the covering material over the ends of the cigar.

Fig. 35 is an end view of the devices shown 85 in Fig. 34.

Fig. 36 is a sectional view taken as indicated by line XXXVI in Figs. 34 and 35.

Fig. 37 is an enlarged detail longitudinal sectional view of a trimming and ironing 90 device for completing the operation upon one end of the cigar.

Fig. 38 is an end view of the device shown in Fig. 37.

95 Fig. 39 is an enlarged longitudinal sectional view of the trimming and ironing device employed for completing the operation upon the opposite end of the cigar.

Fig. 40 is an end view of the device shown in Fig. 39, and

100 Fig. 41 is a transverse sectional view taken upon the plane of line XLI in Fig. 39.

Referring to Figs. 1 and 9, it will be seen that the machine has a supporting framework 1 upon which is mounted a feed hopper 2 and chute device 3 for containing and supplying to the wrapping mechanism of the machine the cigars to be wrapped.

From this hopper 2 the cigars are fed 110 downward in a column and tabled off, one at a time, wrapped roughly in a suitable wrapping material by mechanism indicated at 3, and carried to perfecting or finishing devices or mechanism where they successively pass through other steps; first, at 4, of having the end portions of the wrapping material initially shaped about the ends of the cigar; second, at 5, of having the end portions of the wrapping material gathered or

115 compacted to a better fit over the ends of the cigar; third, at 6, of having the end portions of the wrapping material pressed or smoothed down to fit more snugly over the ends of the cigar; and lastly, at 7, of having the wrapper finally compacted and

120 smoothed, and any excessive or projecting portions of the covering material trimmed off, preparatory to delivery of the cigar with its wrapper completed.

125 The hopper 2 (see Figs. 1, 2 and 3) has

two downwardly converging side walls, as 8 and 9, and two substantially vertical end walls, as 10 and 11. The side wall 8 is stationary, while the side wall 9 is mounted to 5 moved toward or away from the wall 8 for adjusting the width of the discharge or delivery opening at the bottom of the hopper. The end walls 10 and 11 are adjustable toward and away from each other to alter the 10 length of the discharge opening.

The side walls 8 and 9 have openings 12 therein through which extend endless moving belts 13. (See Figs. 2 and 3.) These belts run upon suitably separated rolls 14 15 carried exteriorly of the walls 8 and 9, and are so arranged that the inner lead 15 of each belt traverses the inner face of the wall and serves as an agitating means for causing or insuring proper feeding of the cigars down- 20 wardly into the discharge opening and the chute at the bottom of the hopper. The belts may be driven in any suitable manner; as indicated, the lowermost rollers of the two belts are connected together by a sprocket 25 chain or belt 16, and are both driven by a belt or chain 17 serving as a driving connection to some other moving part of the machines. To take care of adjustment of the wall 9 toward or away from wall 8, a suitable 30 tightener device is provided for the chain 16, in the form of an idler roller 18 swinging at the free end of an arm 19 pivoted upon the shaft of one of the lowermost rollers 14.

From the discharge opening of the hopper 2 extends downward a chute made up of side walls 20 and 21, and end walls 22 and 23. (See Fig. IV.) The side wall 20 is stationary, while the side wall 21 is mounted 40 to move toward or away from the wall 20 for adjusting the transverse width of the passage through the chute. The end walls 22 and 23 are movable toward and away from each other for adjusting the transverse 45 length of the passage.

The side wall 20 of the chute (see Figs. 1 and 9) has fixed thereto a bracket 24 by means of which it is supported at the upper end of a suitable standard 25 rising from the 50 main base plate, or table, 26 of the machine frame, and the side wall 8 of the hopper is secured rigidly to the wall 20 by means of a connecting plate 27. (Fig. 2.) All of the remaining walls of the hopper and 55 chute are supported upon and made adjustable relatively to the walls 8 and 20, as follows:

In the wall 20 are slots 28 (see Figs. 2, 3 and 6) through which extend lugs 29 carried by flange portions 30 of the end walls 22 and 23. These lugs constitute the sole supports for mounting the walls 22 and 23 against the wall 20, and have reduced portions 31 slidably engaging the walls of the

slots 28. There are two of the lugs 29 for each side wall 22 and 23, one adjacent the upper ends of said side walls, and one adjacent the lower ends of said side walls, and each lug has a threaded aperture 32 therethrough. Through the threaded apertures 70 of the lower lugs extends a shaft 33, and a similar shaft 34 extends through the apertures of the two upper lugs. Both of these shafts are suitably threaded to engage the 75 threads of the apertures, and they are geared together by means of suitable gears 35 and 36 and a vertical shaft 37, so that rotation of the shaft 34, as by turning the thumb nut 38, will produce corresponding rotation of shaft 33 and movement of the walls 22 and 80 23 toward or away from each other at both ends in unison, according to the direction of rotation of the thumb nut.

The end wall 10 of the hopper (Fig. 3) 85 is fixed to and carried by the chute wall 23, so as to move rigidly therewith at all times. The end wall 11 of the hopper has at its upper corners a pair of projecting lugs, as 90 39, arranged for selective engagement in any one of a series of notches 40 in the lower edges of slots in the walls 8 and 9. The lower edge portion of this wall 11 hangs just within the upper end of the chute, against the inner surface of its end wall 22. Instead of being a single wall member extending between the end walls 22 and 23, the side wall 21 of the chute consists of two 95 separate strips 41 and 42, Fig. 4, one mounted on each of said end walls, and independently adjustable thereupon. The 100 mechanisms by which these wall strips 41 and 42 are adjustably mounted are identical, as follows:

To the wall strip 41 are attached a pair 105 of bracket pieces 43 and 44 (see Figs. 2 and 4) which are slotted, as at 45, to straddle the wall 22 adjacent its upper and lower ends. The slots 45 receive the adjacent portions of the wall 22 and serve to guide the wall strip 41 and to maintain it at all times 111 in proper relation to the wall 22. They also have properly positioned pivotal connections 46 and 47 for link connections 48 and 49 to levers 50 and 51, adapted for simultaneous 115 operation by means of a common centrally disposed actuating screw 52 which engages the adjacent threaded ends of the levers. (See Figs. 2 and 5.) Rotation of the thumb screw 52 will swing levers 50 and 51 upon their respective pivots 50^a and 51^a on the outer sides of the wall 22, and produce parallel movement of the two bracket pieces 43 and 44, so that both ends of the wall strip 41 will be moved transversely 120 across the end wall 22, toward or away from the wall 20, in unison, according to the direction of rotation of the thumb screw. Since the adjusting devices for the two wall

strips 41 and 42 are independently operable, they may be readily moved to different distances toward or away from the wall 20; this is important, since it enables the wall 5 strips to be placed to the most advantageous position for holding the cigars which, of course, are of different diameters at their opposite ends.

In using this device, a number of cigars 10 are placed in the hopper, which may, of course, be of any appropriate size. The cigars will fill the chute and (if in sufficient number) will pile up within the hopper. The end wall 11 of the hopper is 15 low, so as to give convenient access into the hopper at all times, since it is only necessary that the cigars be so placed in the hopper that their inner ends will abut against the end wall 10. By adjustment of 20 the end wall 11 to an appropriate inclination, moreover, any cigars not initially placed in engagement with the wall 10 will be automatically pushed toward the latter during their descent, by engagement with 25 the inclined surface of the wall 11.

It may be here noted that the driving connections for the agitating belts 15 are such as to cause the portions of the belts within the hopper to move in opposite directions; 30 that is, one belt to move downwardly and the other upwardly. The cigars engaging the belts will thus be caused to rotate gently, so that they will feed into the chute without difficulty.

35 To control the discharge of the cigars singly from the lower end of the column in the chute, a mechanism comprising a pair of stops 53 and 54 is provided (see Figs. 2, 3, 4 and 11) to toll off the cigars.

40 The stop 53 is arranged above the stop 54 and is adapted to retain and support the main column of cigars above, while the stop 54 operates to release the lowermost cigar.

45 The stop 53 consists of a pair of plates 55 and 56 supported at the lower end of a swinging carrier 57, which is pivoted at 58 upon a supporting block 59 adjustably mounted on the outer surface of the wall 20. The means of adjustment for the supporting block 59 consists of a set screw 60 threaded upon a stud 61 projecting laterally from the wall 20 through a vertical slot 62 in said block. The vertical position of the 55 stop 53 with its stop plates 55 and 56 relative to the stop 54 may thus be adjusted at will; this adjustment must, of course, correspond with the diameter of the cigars. To prevent possible injury or mutilation 60 of the cigars when the device 53 enters and engages between them, the stop plates 55 and 56 are made laterally flexible, by being pivotally supported upon their carrying frame 57 (see Figs. 7 and 8), each being

resiliently and yieldingly held in a normally operative position by means of a leaf spring 63 engaging against a square heel of the plate 55 adjacent the hinge.

The stop 54 consists of a pair of plates 64 and 65 carried at the lower end of a 70 swinging frame 66, which is pivoted at 67 upon suitable supporting pieces secured upon the outer surface of the chute wall 20.

The swinging stop frame 57 is operated by means of a crank arm 68 (see Figs. 2, 3, 75 and 4) whose free end carries a pin 69 engaging in a slot 70 in a part 71 of said stop frame. The crank arm 68 is mounted on a shaft 72 rotatably supported in a suitable bearing member 73 fixed to the outer surface of the chute wall 20. This shaft carries at another point in its length a second crank arm 74, at whose free end is a pin 75 adapted to engage in a slot 76 in a vertical slide bar 77, mounted upon the 80 outer face of the chute wall 20. The slide bar 77 may be moved up and down to rock the arm 74 by means of a link 78 connected to its lower end. The link 78 is connected to an extended portion of a movable member 90 199 to be hereinafter described (see Fig. 11), so that the link will move up and down as the member 199 is oscillated in a vertical plane.

To operate the swinging stop frame 66, 95 a second shaft 79 is provided, parallel with shaft 72 and rotatably supported in a bearing member 80. This shaft has at one end a crank arm 81 positioned back of an adjacent portion of the frame 66, at its other 100 end a crank arm 82, positioned to be engaged by a pin 83 (see Fig. 4) which is carried by the slide bar 77.

In operation, an upward movement of 105 slide bar 77 first produces an upward swing of crank arm 74 and a consequent inward movement of the stop frame 57 and the stop fingers 55 and 56 to engage beneath and retain all cigars above them. As the slide bar 77 continues to move upwardly 110 with the pin 75 riding upon its edge surface, the pin 83 engages the arm 82 and causes the stop frame 66 to swing outward and withdraw the stop plates 64 and 65 from beneath the lowermost cigar, allowing said cigar to 115 fall by gravity into the wrapping device 3. Upon return downward movement of the slide bar 77, the pin 83 leaves the arm 82 and allows the stop plates 64 and 65 to return by gravity to position within the 120 chute. The continued downward movement of the slide bar 77 brings the slot 76 again into co-operation with the pin 75 and operates the stop frame 57 to withdraw the stop plates 55 and 56, so that the whole column 125 within the chute may fall on to the top plates 64 and 65. The above-mentioned slot 70 for receiving pin 69 is made of such

length as to properly accommodate said pin, and to enable said pin to fully perform its function of swinging the frame 57, irrespective of vertical adjustment of the frame 5 57.

When the lowermost cigar, as C, drops sidewise from the lower end of the chute, it falls into a cradle 85 provided to receive it directly beneath the chute. (See Figs. 1, 10 9 and 11.) This cradle is formed as a curved flange at the lower edge of an inclined arcuate plate 86 which is mounted upon a pair of arms 87 and 88. These arms are pivoted to swing on a shaft 89 (see Fig. 10), and the 15 curve of the plate 86 is such that the outer face thereof is substantially concentric with said shaft. Within the cradle 85 is arranged a piece of wrapping material 90, such as tin foil or the equivalent, in which the cigar is 20 wrapped. An operating link 91 is connected with the arms 87 and 88, and also with suitable operating elements for swinging or oscillating the cradle 85 and the plate 86 up and down about the center of the shaft 89. 25 The lower end of the link 91 is pivotally connected, as at 291, with one end of an arm 292 which is fixed to a rock shaft 293. At another point in the length of this shaft a second arm 197 is fixed, and a link 198 is connected between the outer end of this second arm and the eccentric strap 155 surrounding the eccentric 156 on the shaft 125. The tin foil is in strip form, and is fed downward upon the plate 86 and to the cradle 85 from a 30 supply roller 170 (Fig. 10), as will be hereinafter set forth. Periodically, just after each cigar falls, a reciprocating cutter 93 (Figs. 9, 11, 12 and 15) operates to sever the strip at a proper point on its way to the 35 cradle so as to cut off a proper portion (including that in the cradle 85) for wrapping a cigar.

Periodically, about as the plate 86 moves downwardly, the tin foils feeds down also; 40 and as the plate 86 rises, the lower or leading edge of the piece of tin foil is engaged by the curving surface of the cradle and is made to curve outwardly and upwardly, so that it forms in effect a liner for the cradle 45 at the time when the cigar falls sidewise into the cradle; i. e., the lower edge of the tin foil stands in a position substantially as indicated at 94. As the leading edge of the tin foil reaches the curve of the cradle 85, during the rise of the cradle (before the dropping of the cigar), a folder device 95 swings over close to the plate 86 just above the cradle 50 and serves as a guide to insure its curling in the manner just described instead of curling or buckling in the opposite direction. The device 95 at once recedes again to allow the cigar when dropped to fall upon the tin foil in the cradle. After the dropping of the cigar, the folder device 95 immediately swings forward again and operates to fold over or turn 55

in the upstanding leading portion of the tin foil on the cigar. At this same time, the cradle and plate start to swing downwardly, so that the cigar is caused to roll gently downward between the plate 86 and an opposing inclined arcuate plate 96. The cigars are received between the members 86 and 96, as they periodically drop from the chute into the cradle 85, when the cradle 85 and the plate 86 are about in their uppermost positions. By the time the parts reach the position as indicated by dotted lines in Fig. 11, the tin foil will be rolled and wrapped entirely around the cigar by the co-acting members 86 and 96. 70 75 80

The folder device 95 is pivotally mounted upon a pivot rod 97 carried by plate 96, and it is provided with an arm 98 extending beyond the pivot and turned laterally to engage within a slot 99 at the lower end of a lever 100. (See Fig. 9.) The lever 100 is pivotally mounted upon a stationary pivot 101, and its upper end carries a roller 102 positioned to be engaged by a cam member 103 arranged to swing with the plate 86 about the shaft 89. The cam 103 is of appropriate shape to cause the folder device to operate in proper timed relation to the downward movement of the cigar, etc., as above described. 90 95

The cutter 93 (see Figs. 9, 11, 12, 15 and 17) consists of a small knife edge wheel or roller rotatably mounted at one end of a slide bar 104. Two guide rods 105 are fixed parallel with the slide bar 104, and a cross head 106, carried by the slide bar adjacent to the cutter roller, engages these guide rods to retain the cutter roller in proper cutting association with an underlying stationary plate or platen 107 over which the tin foil passes. The outer end of the slide or cutter bar 104 is connected with the upper end of a lever 108 by means of suitable links 109, and the lever 108 extends into operative connection with a cam 110 mounted upon the main drive shaft 111 of the machine, Fig. 17. The lever 108 is 110 pivoted intermediate its length, as at 112, and the shape of the cam 110 is such that the cutter roller is caused to move in one direction across the surface of the platen 107 to cut off a piece of tin foil for one cigar and to move in the opposite direction backwardly across the surface of platen 107 to cut off another piece of tin foil for the next cigar. The cutter roller stands idle at the opposite extremities of its reciprocatory movement 115 while the tin foil is being fed downwardly to the cradle. 120 125

Two clamp plates 113 and 114 (Figs. 11 and 12) are provided for retaining the wrapping material (as tin foil) against movement while the cutter roller 93 is in operation. The clamp plate 113 is arranged just above the cutter, and is pivotally mounted by its opposite ends upon pivots 115 carried by the plate 107. The clamp 130

plate 113 is thus supported to swing about a longitudinal axis, so that the lower longitudinal edge of the plate is adapted to swing into and out of engagement with the surface 5 of the wrapping material throughout its width and hold it fast on the platen 107. At one upper corner of the plate 113 is an operating stud or arm 116 by which the plate is moved. The clamp plate 114 is 10 arranged just below the cutter and operates in the same manner as the clamp plate 113, being supported at its opposite ends in bearings 117 fixed to the plate 107. A stud arm 118 is provided for operating it. This 15 clamp plate 114 holds the wrapping material fast on a plate 118^a (subjacent to the platen 107, and forming in effect an extension thereof) which curves downward over the plate 86.

20 The operating arms 116 and 118 for the clamp plates extend to the same side of the respective pivotal axes of the plates, and they are connected to a single equalizing bar 119 which is itself pivotally connected with an 25 operating rod 120, by which it is lifted to move both the clamp plates into clamping position at each operation of the cutter. The rod 120 is connected with the equalizing bar 119 intermediate the arms 116 and 30 118, so that the two clamp plates will be moved to clamping position with properly uniform pressure at all times.

The operating rod 120 (see Figs. 9, 10 and 11) extends downwardly, and its lower 35 end is connected with one end of a rock lever 121 which is pivoted on the main frame at 122 intermediate its ends, and has at its other end an anti-friction roller 123 positioned to engage a cam 124 mounted upon an auxiliary drive shaft 125, connected with the main drive shaft 111 by suitable gears 126 and 127. A tension spring 128 connected with the rod 120 urges the rod upwardly to maintain the roller 123 at all times in engagement with the surface of its cam 124, 40 and to normally hold the clamp plates 113 and 114 in clamping position.

In order to seal up the wrapped cigar air-tight, to keep the completed wrapping 50 from being accidentally displaced, and to hold the initially wrapped material about the cigar during various operations in the machine, it is necessary to apply an adhesive agent, such as gum, to the wrapping material to hold its outer edge in place when rolled about the cigar. In the machine as 55 illustrated, this gum is applied to the surface of the wrapping material before the operation of the cutting mechanism. The device 60 for thus applying the gum to the wrapping material may take any appropriate form, but preferably consists of the mechanism illustrated, which may be described as follows (referring to Figs. 9, 11, 12 and 13):—

65 A gum box 129 is positioned at one side

of the strip of wrapping material, and a gum carrier device 130 is adapted to move between the supply in the gum box and the wrapping material to take up, carry, and apply or deposit the gum on the latter at 70 regular intervals. Within the box 129 is mounted a roller 131 which may be slowly rotated by means of a suitable ratchet wheel device 132 connected therewith. The gum carrier consists of an elongated body portion 75 133 at one edge of which is carried a felt, rubber, or other soft gum-conveying piece 134. These parts are in turn mounted upon a sleeve 135 freely rotatable on a short shaft 136. The shaft 136 is rigidly connected 80 with, and projects laterally from, a cross shaft 137 which carries a gear 138 meshing with a sliding rack bar 139. The shaft 137 is mounted to rotate in bearings 140 and 141 in a stationary supporting frame or plate 85 142. Sliding movement of the slide bar 139, therefore, will swing or oscillate the gum carrier 133 back and forth 180 degrees between the gum wheel and the wrapping material. The sleeve 135 carries a bevelled 90 gear 143 in mesh with a stationary bevelled gear 144 carried by the bearing 140, and by this means the swinging movement of the gum carrier from the gum roller over upon the wrapping material causes the gum carrier to turn about the shaft 136 just sufficient to shift the gum-conveying piece 134 from a correct gum-roller-engaging position to a correct wrapper-material-engaging position. 95

The plate 142 is extended beyond the shaft 137 to a position overlying the wrapping material, and it has an opening 145 through which the gum carrier may reach the wrapping material. Directly beneath this opening 145 is a stripper plate 146 also having an opening, as 147, registering with opening 145 to permit free passage of the gum carrier. At its upper edge the stripper plate 146 is pivotally connected with the plate 142 by means of a pivot shaft 148, and it carries a pin 149, which projects upwardly through the plate 142. A compression spring 150 is mounted on this pin 149 (Fig. 11), between its head 151 and the plate 142. 110

The pin 149 is so positioned that its head 151 will be engaged by a leaf spring 151^a on the sleeve 135 of the gum carrier when the gum carrier swings over to deposit gum upon the wrapping material, so that as the gum carrier moves through the openings 145 and 147 against the wrapping material, the stripper plate will be actuated by the carrier and pressed downwardly into engagement with the wrapping material, and will serve to hold the wrapping material firmly against the underlying stationary plate 152 (which overlies the platen 107 and in effect forms an upward extension thereof). The wrapping material is thus 125 130 135

held fast on the plate 152 (under control of the gum carrier), both while the gum is being applied and also while the gum carrier is being lifted away from the wrapping material on its return movement toward the gum roller. By this means, a clean and correct gumming is ensured, since there is no opportunity afforded the wrapping material to lift upwardly with the gum carrier, 10 which lifting, would naturally smear the gum objectionably on the adjacent parts of the mechanism, interfere with the easy downward travel of the wrapping material, and result in an interruption of the smooth 15 operation of the device.

The slide bar 139 may be connected for operation in any suitable manner; as indicated, it is arranged to be operated by a rock lever 153 (see Figs. 9, 10, 12 and 13) 20 which extends substantially vertically downwardly from the rear end of the rack bar into pivotal connection with an attaching piece 154 on a strap 155 surrounding an eccentric 156 fixed upon the drive shaft 125, 25 the connecting pivot being shown at 157. The rotation of the shaft 125 causes the lever 153 to rock back and forth upon a pivot 158 which is arranged intermediate the length of the lever, thus producing the 30 proper reciprocatory movements of the rack bar 139.

Since the diameter of cigars of different makes differ materially, it is essential that the length of the wrapping material cut off and the position of the gum upon the wrapping material may be altered at will. For this purpose the gumming mechanism 35 may be mounted upon a separate frame 159 adjustably attached to the stationary frame part 160 by means of suitable screws 161 that extend through slots in a transversely extending flange of the frame 159 and have screw threaded engagement with a flange member 160^a that is secured to the 40 frame 160 (Figs. 9 and 13), the direction of adjustment being parallel with the inclined plane of the plate 107. The cutting mechanism is made adjustable by mounting it directly upon the plate 107 and by adjustably attaching said plate itself to the stationary frame 160, as by means of bolts 193 screwed into flange portions 194 of the stationary frame and engaging in slots 195 in the plate 107. (See Fig. 12.) The rod 45 120 for operating the clamps 113 and 114 may be provided with a suitable device 196 (Fig. 11) for altering its length to suit the adjusted position of the cutting mechanism and to insure that the clamps 50 shall at all times move to correct clamping position. In order that the rock lever 153 may correctly swing the gum carrier in all adjusted positions of the gumming mechanism, the central pivot 158 of the rock lever is made adjustable. For this purpose

the bracket piece 162 with which the pivot pin 158 engages is attached, by means of a fastening screw 163, to an inclined supporting plate 164, the angle of the inclination of said plate being the same as that 70 of the plate 107, and hence parallel to the path of adjusting movement of the frame 159 and the rack bar 139. The connection between the pivot pin 158 and the rock lever 153 is by means of a sleeve 165 slidably mounted upon the rock lever, so that the pivot pin shall be free to move longitudinally of the rock lever with any adjustment of the bracket piece 162 along the 75 supporting plate 164. By this means the 80 operation of the gum carrier will be uniform in all adjustments of the frame 159.

To maintain the level of the gum in the gum box 129 substantially constant, there is provided a suitable float 166, Fig. 13, to 85 which is attached an upstanding arm 167 carrying an adjustable weight 168. The float is pivotally mounted in the walls of the gum box by a pivot 169, and is adapted to swing about this pivot as the level of 90 the gum is raised or lowered. As the level of the gum is lowered, the float will swing downwardly and bring the weight 168 to that side of the vertical plane of pivot 169, so that a proportion of the weight 95 will be added to the weight of the float, according to the amount of downward swing of the latter. The greater the weight thus applied to the float, the more the float will sink into the gum, and hence the more 100 gum will be displaced by the float. An approximately constant surface level of the gum may be thus maintained.

The wrapper material 90 is supplied from a spool or roll 170, and is fed downwardly 105 across the plate 107, after each operation of the cutter by means of a strip 171 of other material, for example, tissue paper, which is wound upon the roll 170 with the wrapping material. (See Figs. 9 and 10.) This strip, which may for convenience be termed a feeder strip, extends over a cross bar 172 at the upper end of a swinging frame 173, which is mounted upon a pivot 174. Below the cross bar 172, the 110 feeder strip passes between a stationary cross bar 175 and a movable cross bar 176 constituting a gripping device by which to hold the lower portion of the strip fast and 115 stationary during the movement of the cross bar 172 above. While the feed strip 171 is held fast, the cross bar 172 is swung outwardly to press against it at an intermediate point and thus pull on it and draw it (and the wrapping material) downward from the 120 supply roll 170. The swinging frame 173 has a pair of laterally extending arms 177 and 178 between which extends a cross shaft 179. To this cross shaft is pivotally 125 connected a pair of operating rods 180, the 130

lower ends of said rods being pivotally engaged with members 181 carried by the arms 87 and 88 below the pivot rod 89. (See Fig. 11.)

5. As a result of these connections, each periodic downward movement of the cradle 85 will be accompanied by an outward movement of the cross bar 172 and a consequent rotation of the spool 170, it being understood that at this time the clamp device 175, 176 will be in clamping position holding fast the lower portion of the feeder strip. The amount of rotation of the spool 170 and the length of wrapper material fed downwardly beneath the cutter 93 on to the wrapping plate 86 will be determined by the extent of lateral movement of the cross bar 172 against the feeder strip; and this may readily be adjusted by 15 adjusting the position of the cross shaft 179 in slots 182 in the arms 177 and 178. This last adjustment may be made and fixed by means of collars 183 and clamp nuts 184 on said shaft 179.

25. The movable cross bar 176 (Figs. 9 and 10) of the clamp device for holding the feeder strip is carried by a swinging frame 185, which is supported upon a pivot 186 and has a forwardly extending arm 187, to 30 which is pivotally connected the upper end of an operating rod 188. The rod 188 has its lower end pivotally connected with a rock lever 189, which is itself pivoted at 190 on the main frame of the machine and extends 35 into operative association with the cam 124; as shown, it engages with the upper surface of the rock lever 121 adjacent to the cam 124. A helical compression spring 191 engaged between a shoulder 192 of the rod 40 188 and the upper surface of the table 26 urges the rod upwardly at all times, while the cam 124 acts to pull the rod downward at each revolution. The spring 191 also serves to hold the end 290 of the lever 189 45 firmly against the adjacent end of the lever 121. The rock lever 189 is of suitably resilient character, so that it will give, or bend, to an appropriate extent under the pressure of the cam 124 after the clamp rod 176 has 50 been moved to full clamping position. This insures proper clamping operation of the clamp rod 176 at all times, notwithstanding slight imperfections in structure and wear of the cam and other moving parts.

55. The arms 87 and 88, Fig. 11, which carry the plate 86 and the cradle 85, are supported so that said plate and cradle may be readily adjusted toward and away from the pivot shaft 89, and, consequently, nearer to, or farther from, the plate 96, this adjustment being for the purpose of enabling the mechanism to properly operate upon cigars of different diameters. In order to provide for this adjustment, the arms 87 and 88 are 60 not themselves directly connected with the

pivot shaft 89, but are arranged to slide in channel members 199 and 200 of a frame which is mounted upon said pivot shaft and to which the operating rod 91 is connected. The arms 87 and 88 are held against displacement in the channels 199 and 200 by clamping collars 201 attached to said channels and to a cross plate 202, to the central portion of which latter the operating rod 91 is pivotally connected. The lower end 70 portions of the arms 87 and 88 (Figs. 9, 10, 11 and 14) have longitudinal slots 203 through which the shaft 89 extends. Just below the shaft 89 the arms 87 and 88 are bent toward each other to provide lug portions 204 substantially parallel with the shaft, and through each of these portions 204 extends a screw 205, which is threaded in an aperture 206 formed in the shaft 89 and has shoulders 207 for engaging the portions 204 of the arms to cause the arms to move longitudinally with the screws. Concurrent rotation of the screws 205 and equal movement of the arms 87 and 88 are assured by a shaft 208 having at its opposite ends bevelled gears 209 meshing with bevelled gears 210 carried by the screws. A squared end, as 211, may be provided upon one of the screws 205 for rotating the same. The pivotal parts 181 (upon which are pivoted the rods 180 for operating the feeder strip cross bar 172) are carried by and adjustable with the arms 87 and 88, so that whenever said arms are adjusted to move the plate 86, for instance, away from the plate 96, then said pivotal parts 181 are likewise moved a corresponding distance away from the pivot shaft 89. Hence, the mere rotation of one of the screws 205 will at once alter the position of plate 86 relative to plate 96 to accommodate a cigar of relatively greater diameter and cause a correspondingly greater length of wrapping material 90 to be fed downwardly under the cutter. 100

110. As the cradle 85 reaches the lower extremity of its swing, considerably below the dotted position shown in Fig. 11, the cross piece 202 strikes one end of a lever 212. (See Figs. 9 and 11.) This lever 212 is pivoted upon the table 26 at 213; and when 115 it is struck by the cross piece 202, its opposite end is made to rise beneath the adjacent end of an arm 214 which is rigidly connected with the plate 96. The plate 96 is pivotally mounted upon the table 26 at 215, so that when the lever 212 is actuated the plate 96 is caused to swing slightly (in a direction away from the pivot shaft 89) out of engagement with the cigar which has just been wrapped. This separation of the wrapping members 86 and 96 releases and leaves the cigar free to fall by gravity into a suitable carrier or transfer device 216, which swings in above the cradle 85 as the latter reaches its lowermost position, the 120 125 130

cigar having been virtually lifted from the cradle by the rolling between the plates 86 and 96. To facilitate the reception of the cigar by the device 216, the cradle 85 and 5 the adjacent portion of the plate 86 are formed with one or more suitable openings, as 217, Fig. 12, to accommodate said carrying device 216. The transfer device 216 takes the cigar and moves it laterally away 10 from the cradle into position to be received and taken by the holding means of the perfecting mechanism.

The plate 96 is preferably lined, as at 218, with some suitably soft material, as velvet 15 or the like, to give proper friction and insure a rolling action of the cigar between said plate and the plate 86. In order to prevent this material from being injured during the upward movement of the cradle, it is 20 desirable to provide the actuating arm 214 of the plate 96 with an extension hook 219 positioned to overhang and engage a laterally extending portion of the arm 187 of the feeder strip clamping device (Fig. 9). By 25 this means, the plate 96 will be held in its outer non-operating position whenever the clamping device is in non-clamping position, which is during the period of upward movement of the cradle, against the pull of a 30 light tension spring 220, provided for yieldingly urging and returning the plate 96 to its operating position.

A convenient way of operating the ratchet device 132 is by a link 222 extending downward from said device into a position where its lower end will be engaged by the arm 197 of the cradle-operating mechanism. By 35 this means the gum roller may be turned the distance of one or more teeth at each 40 operation of the cradle mechanism.

The carrier device 216 may take any desired form; as illustrated, it consists of a trough 224 with an attached weight 223 for keeping it at all times facing upwardly, the 45 whole being pivotally mounted, as at 225, on the outer end of an arm 226 (Fig. 9) carried by a rock shaft 227. Upon the shaft 227 is fixed a disk 228 to which is pivotally connected an operating link 229, whose lower 50 end is pivotally connected, as at 230, with a bevel gear 231 arranged to be driven by a co-operative bevel gear 232 carried by the shaft 125. Rotation of gear 231 will cause the shaft 227 and the arm 226 to rock back and forth, and this movement is so timed 55 that the carrier device 216 will properly receive and properly discharge the cigars.

Fixed upon the shaft 125 are a pair of cams 233 and 234, which operate small 60 plungers 235 and 236, respectively (see Figs. 9, 12, 15 and 16). These plungers are arranged substantially in alignment with each other, and in such positions that their ends or heads are adapted to move into and out 65 of engagement with the adjacent opposite

ends of a cigar just after the cigar has fallen into the cradle 85 from the hopper chute 20, so as to bring the cigar to a definite lengthwise position on the tin foil in the cradle. The head 236^a (see Fig. 12^a) of the plunger 70 236 is carried by a small rod 236^b arranged to slide in a bore in said plunger. This rod 236^b is urged outward by a helical compression 236^c as far as permitted by a pin 236^d in said rod, which projects outwardly into a 75 slot 236^e in the plunger. The plungers 235 and 236 are slidably mounted in suitable stationary frame parts 237, and are connected by links 238 with the upper ends of levers 239 and 240, respectively. The lever 239 is 80 pivotally mounted at 241, and its lower end is pivotally connected at 242 with one end of a slide bar 243, whose opposite end carries an anti-friction roller 244 bearing against the cam 233. A suitable compression spring 245 urges the slide rod 243 toward the cam. The lever 240 is pivotally mounted at 246, and its lower end is pivotally connected at 247 with one end of a slide 85 bar 248 carrying an anti-friction roller 249 90 which bears against the cam 234. A suitable compression spring 250 urges the roller 249 against its cam.

The shapes of the cams 233 and 234, for projecting inwardly the plungers 235 and 236, are such as to cause the plungers 235 and 236 to bear or push against the opposite ends of the cigar at once, but they preferably differ slightly, nevertheless, in order that the plunger 235 shall be held against 100 the cigar for an appreciable period, during which the plunger 236 is coming up to the cigar and moving away again. For a suitable time, therefore, the plunger 235 will be maintained in proper definite position to 105 serve as a stationary abutment against which the cigar may be pushed endwise by the plunger 236. It is for this purpose that the cam 233 has the high dwell surface 251, as distinguished from the non-dwell high point 110 252 of the cam 234. The resiliently yielding mounting of the plunger head 236^e serves to obviate injury of specially long or oversize cigars. To ensure that the plunger 236 shall be properly withdrawn from against the 115 cigar in time to permit an unobstructed downward movement of the cradle, the cam 234 is provided with a pin 253 which is adapted to engage against the surface 254 of the slide rod 248 and thus positively retract the rod as fast as the receding surface of the cam 234 permits. The pivot devices 241 and 246 for the levers 239 and 240, respectively, are mounted in slots 255 in the machine frame and are slidably adjustable 120 lengthwise of the levers to provide for adjustment of the thrust of the plungers 235 and 236.

In discharging a cigar, the carrier device 216 simply "dwells" with the cigar in the 125 130

position indicated at 256^c in Figs. 1 and 9. At that point the cigar is taken by one of a series of grippers 257, which are carried at the outer ends of carrier arms 258 (Figs. 1 and 17), arranged like the spokes of a wheel. This rotary carrier is fixed on a central shaft 259, which is rotatably mounted in suitable bearings 260, concentric with the perfecting stations 4, 5, 6, 7. To one end of this shaft 259 is fixed a disk 261 (Fig. 20) carrying a plurality of axially projecting pins 262 spaced apart equidistant adjacent its periphery. Mounted adjacent to this disk is a cross shaft 263 upon which is fixed a second disk 264 having a cam extension 265 offset therefrom for engaging the pins 262 and camming said pins so as to rotate the shaft 259 clockwise, as seen in Fig. 1. The disk 264 has a peripheral cut-out at 266 to permit passage of the pins as they are moved by the cam 265, the remaining peripheral portion of the disk 264 being plain and uninterrupted, so as to travel between the pins 262 without causing or permitting any movement of the rotary carrier. Thus, a satisfactory and efficient step by step motion is given the wheel with the grippers 257, so as to carry the cigars successively from one of the concentric stations 4, 5, 6, 7 to another during the operation of the machine, with a dwell at each station.

The shaft 263 may be driven from the shaft 125 by means of a chain or belt drive 267.

Loosely mounted upon the shaft 259 is a crank device comprising a collar 268 with a pair of radial arms or lugs 269 and 270. (See Figs. 17 and 21.) To the arm 269 is pivoted a slide bar 271 which extends radially with reference to the shaft 259 in one direction, while to the arm 270 is pivotally connected a second slide bar 272, which extends radially with reference to the shaft 259 in a different direction. To the bar 271 is pivotally connected, at 273, one arm of a bell-crank lever 274, which is itself pivoted intermediate its length at 275, and carries at its opposite end an anti-friction roller 276, which engages a cam 277 fixed to the main drive shaft 111. The position of the slide bar 271 corresponds with the position occupied by one of the gripper devices 257 at the time when said gripper device is receiving a cigar from the carrier device 216, and the position of the slide bar 272 corresponds with the position of the gripper device after the same has successively passed the mechanisms 4, 5, 6 and 7 and has reached a position where it is ready to discharge the finished cigar upon the receiving table 278, Fig. 1. Said slide bars 271 and 272 are adapted to operate the gripping devices 257 to cause them to grip and release, respectively, in these two positions.

The grippers 257 are all of identical construction. Each consists (Figs. 22, 23, 24 and 25) of a pair of members 279 and 280, which are mounted to slide lengthwise of the arm 258 upon suitable guides 281 at the outer end of the arm. Each of the slide members 279 and 280 has a toothed surface 282, and an intermediate gear 283 is rotatably mounted upon the arm in mesh with these toothed surfaces, so that movement of one slide member will cause a like movement of the other slide member in the opposite direction; in other words, the jaws 257 are constrained to move in unison toward or away from one another. Both slide members 279 and 280 are equipped with jaws 284 adapted to grip and hold the cigar. A rod 285 extending from the slide member 280 is connected to an abutment collar 286 mounted upon the arm 258 and urged outward by a compression spring 287 acting against an abutment shoulder on the arm 258, so that the jaws are resiliently biased to close, and are normally urged together and held closed by, said spring. The collar 286 has a projection or lug 288, which is in position to be engaged by hook lugs 289 at the ends of the slide bars 271 and 272.

Just when the carrier wheel with the arms 258 has rotated to bring one of the gripping devices 257 into position to receive a cigar from the carrying device 216 and the collar lug 288 is in the path of movement of the lug 289 on the slide bar 271, the lever 274 moves said slide bar 271 toward the shaft 259, thus opening the jaws 284 ready to receive the cigar. The jaws close upon the cigar and remain closed, holding the cigar firmly between them until the arm has passed around to discharging position.

After a cigar has been received from the carrying device 216, the first step movement of the gripper device 257 will carry the cigar into position to be operated upon by the mechanism at 4. (See Figs. 1, 17 and 26 to 30.) It consists of two separate wrapper-shaping devices 294 and 295, one for operating upon one end of the cigar and the other for operating upon the other end of the cigar. The device 294 is carried by a shaft member 296, which is fixedly supported in a frame 297 slidably mounted upon a pair of spaced guide rods 298. The device 295 is carried by a shaft member 299, which is fixedly supported in a frame 300 slidably mounted upon a similar pair of guide rods 301. Other perfecting wrapping mechanisms at 5, 6 and 7 are likewise mounted on these movable frames 297 and 300 at opposite sides of the path of movement of the rotary carrier with the gripping devices 257, and hence similarly adapted to be advanced into concurrent operation on the

ends of the cigars or retracted to permit movement of the cigars by the movable carrier with the grippers 257.

The two devices 294 and 295 are of identical construction, and a detailed description of one will suffice for both.

Fixed to the end of shaft 296 is a collar 302 having an enlarged slotted portion 303 providing pivotal mountings for a series of double ended "finger" levers 304, which are pivotally mounted intermediate their length, as at 305. Their forward ends are curved inwardly toward the axis of the shaft 296, and have thereon wrapper-engaging elements in the form of rollers 306. The opposite ends of the levers extend toward the opposite end of the shaft, and are fitted with anti-friction rollers 307. The collar 303 is provided with suitable resilient means, as spring-actuated plungers 308, for urging the rollers 306 convergently toward each other at all times. The collar 302 is also preferably provided with a flange 309 slotted at 310 to serve as guide means for the levers 304 and keep them parallel with each other. Slidably mounted on the shaft 296 is a funnel-shaped cam member 311 adapted to be shifted lengthwise of the shaft and to telescope over the ends of the levers that carry the rollers 307, so as to move said ends toward each other and expand or spread apart the rollers 306.

The frame 297 (Fig. 17) has a cross rod 312, which is engaged in the slotted upper end of an operating lever 313. This lever is pivotally mounted upon the main frame at 314, and its lower end is bifurcated and fitted with anti-friction rollers 315 bearing upon cams 316 and 317. These two cams are shaped to maintain constant engagement with the rollers at all times and to swing the lever back and forth. A link 318 connects the lever 313 to the lower end of a second operating lever 319, which is pivotally mounted upon the main frame at 320 and has its slotted upper end engaged with a cross rod 321 carried by the frame 300. By these connections, the frames 297 and 300 are made to move simultaneously toward and away from each other at properly timed intervals. A lever 322 with its lower end pivoted on the frame 297 at 323 has a bifurcated upper end with slotted sides engaged with pins 324 on the funnel-shaped cam 311 of the device 294. (Fig. 17.) In the path of this lever 322, as it is bodily moved backward with the movement of the frame 297, is a stationary stop 325 adapted to engage the lever 322 and cause it to swing forward and move the cam 311 over the adjacent ends of the levers 304 of the device 294, so as to cause the opposite ends of said levers to swing from closed to open position. When the lever 322 has been thus swung and the cam 311 thus actuated,

the lever 322 is temporarily held against return movement by a spring catch 326, which automatically engages in a notch 327 in a rack member 328, also movable with the frame 297; and thus the rollers 306 are kept apart as the device 294 is advanced upon a cigar.

As the frame 297 moves forward toward the frame 300, the head portion of the catch 326 engages a stationary cam 329, which lifts the catch out of the notch 327. (Fig. 17.) Just as the catch moves out of the notch, the lever 322 strikes a stationary stop 330, which swings the lever back and carries the cam 311 out of engagement with the levers 304, so as to allow the outer ends of said levers to move to closed position and bring the engaging elements 306 together upon the cigar and its wrapper.

The funnel-shaped cam 311 of the device 295 is provided with similar operating means, indicated generally by the reference character 331, for shifting it to control the convergence and expansion of its wrapper-engaging elements.

By this construction, the wrapper-engaging elements 306 of the two devices 294 and 295 are caused to move into and out of closed, i. e., cigar-engaging, positions at regular intervals timed to correspond, with the back and forth movements of their carrying frames 297 and 300. As the frames move toward each other for operating upon a cigar which has just been brought into proper alignment by one of the gripping devices 257, the elements 306 stand open so as to pass readily over the ends of the cigar. As the frames reach their innermost nearest positions, the cams 311 are moved backwardly, and the elements 306 close upon the cigar and its wrapper. The frames then move apart, retracting and dragging the rollers 306 outwardly over the loose ends of the wrapping material which surrounds the cigar, and causing said wrapping material to be more or less uniformly gathered in and creased or pleated lengthwise of the cigar to conform roughly to its contour. The spring devices 308 meanwhile serve to keep the rollers 306 together in contact with the wrapper and hold them resiliently to their work. After the rollers 306 have left the cigar entirely, the cams 311 are actuated again to spread the levers 304 apart preparatory to a repetition of the operation on another cigar.

The heads 302 that carry the levers 304 have extensions 332 that afford pivotal support, as at 333, for a pair of levers 334 and 335. (Figs. 27, 28 and 29.) These levers 334 and 335 are fitted with anti-friction rollers 336 at their rear ends, adjacent the rollers 307, and are adapted to be operated upon by the cams 311 in the same manner as

the levers 304. As shown in Figs. 27, 28 and 29, each of the levers 334 and 335 has a laterally outstanding pin 349, on which is mounted a compression spring 350 which bears upon a yoke member 351 carried by the collar 302. These yoke members 351 are pivotally connected with the collar 302 and serve as guides for the levers, while the springs 350 normally keep them in closed position. At its forward end, the lever 334 has a pair of spaced arms 337 and 338 carrying spring finger members 339 and 340, respectively, between the free ends of which is connected a suitable soft wrapper-engaging element, such as a cord 341. At its forward end, likewise, the lever 335 has a pair of spaced arms 342 and 343 carrying spring fingers 344 and 345, respectively, between the free ends of which is connected a second wrapper-engaging element or cord 346. The bights of the cords 341 and 346 are supported intermediate the ends by a pair of suitable arms, as 347, freely pivoted at 348 upon the collar 302, so as to form an open loop for encircling the cigar.

The spring fingers 339, 340, 344 and 345 are tensioned to spread apart and hold the connecting elements 341 and 346 stretched into substantial parallelism with each other when the levers 334 and 335 are in open position. When the levers 334 and 335 move to closed position about an interposed cigar, however, the connecting elements or cords are caused to wrap around the cigar from opposite sides, as indicated most clearly in Figs. 28 and 30, thus pressing against the wrapping material of the cigar with a uniform pressure from substantially all directions. The connecting elements or cords 341 and 346 are arranged in advance of the rollers 306 of the levers 304, so that they follow said rollers 306 as the rollers are drawn off the ends of the cigar. They thus serve to fold, press and smooth down the outstanding creases or pleats of the wrapping material in the spaces between the rollers 306.

The connecting elements or cords may be thus appropriately referred to as smoothers, or smoothing elements; their convergence or contraction and their expansion are controlled by the longitudinal shifting of the cam members 311, in the same manner as that of the elements 306. Taken together, they form flexible loops, adapted to be drawn taut by the fingers about and along the cigar during the retraction of the devices 294 and 295.

After a cigar has been received from the carrying device 216, the second stop movement of the ripper device 257 will carry the cigar into position to be operated upon by the mechanism at 5. While the mechanism at 5 may be a substantial duplicate of that at 7, as shown, (see Figs. 1, 17 and

81 to 33), it consists of two separate rotating devices which may be termed "gatherers", because they operate to gather in upon themselves or compact the end portions of the wrapping material which project loosely at and adjacent the extreme ends of the cigar.

The two gatherers are identical, and each consists of a pair of pivoted jaws 352, and suitable means for opening and closing and for rotating said jaws. The jaws 352 have registering semi-cylindrical longitudinal grooves 352a (Figs. 31 and 33) in their faces for receiving the extreme ends of a wrapping; they cause the material to fold together in a circular fashion as they come together while rotating about it, thus compacting the extreme ends of the wrapper and bringing them to a closer fit on the extreme ends or tips of the cigar. This operating means consists of a toggle 353 connected with the jaws, and a slideable operating rod 354 which extends axially through a hollow shaft 355 and is connected at its rear end with a collar 356 slideable on the shaft 355, the connection between rod 354 and collar 356 consisting of a cross pin 357 movable in slots 358 in the shaft. The shaft 355 is mounted to rotate in bearings 359 carried by the frame 297, but is held against longitudinal movement in said bearings by means such as collars 360 and 361 fixed thereon and engaging the bearings. The jaws 352 are pivoted to the collar or flange 361 at the forward end of the shaft, and a suitable gear 362 is fixed to the shaft for driving it. This gear 362 is driven by a gear 398 associated with the mechanism at 6.

A lever 363 engages the collar 356 for sliding the toggle rod 354 back and forth during the operation of the machine. As shown in Fig. 19, the lower end of this lever is pivoted at 364 on the frame 297, and it is provided with operating mechanism for closing and opening the jaws 352 which is substantially a counterpart of that above described for the cams 311; that is, it carries a spring latch 365 arranged to co-operate with a ratchet member 366 to hold the lever in one position after it has been swung by engagement with the stationary stop 367 when the frame moves backward toward said stop, and a stationary cam 368 is provided for releasing the spring latch from engagement with the ratchet device 366 when the frame moves forward. In the present instance a spring 369 is arranged within the shaft 355 for swinging the lever 363 backward and closing the jaws 352 upon release of the spring latch 365 and for holding the jaws 352 normally closed.

The operating mechanism for the jaws carried by frame 300 is of the same construction.

At the time when a cigar is brought by one of the gripper devices 257 into alignment with the gatherers, the gatherers move toward each other in open position; and when they are fully advanced, the spring latches 365 release and allow the springs 369 to close the jaws against the wrapping material of the cigar. Both of the gatherers are constantly rotating, and as they close about the ends of the wrapping material, they operate to compact them to a closer fit, as already explained.

After a cigar has been received from the carrying device 216, the third step movement of the gripper device 257 will carry the cigar into position to be operated upon by the pressing and smoothing mechanism at 6. (See Figs. 1, 17, 18 and 34 to 36.) It consists of two separate devices of substantially identical construction, one carried by the frame 297 and the other by the frame 300. Each of these devices comprises a supporting shaft 370 non-rotatably mounted in spaced supporting standards 371 (Fig. 18) carried upon the frame 297 or 300, as the case may be. To one end of this shaft is fixed a bevelled gear 372 which is constantly in mesh with a pair of bevelled pinions 373, which are rotatable upon stub shafts 374 carried by a frame 375. (Figs. 34 and 35). The frame 375 is secured on a sleeve 376 which is rotatable on the shaft 370, and this sleeve extends through one of the bearings 371 and carries a bevelled gear 377, Fig. 18, by which it is driven from an upright shaft 378 by means of a bevelled gear 379 at the upper end of said shaft. The shaft 378 has at its lower end a bevelled gear 380, which meshes with a bevelled gear 381 mounted upon the drive shaft 125. Suitable universal and slide joints 382 and 383, respectively, in the shaft 378, permit the back and forth sliding movements of the frame 297.

Bevel gears 384 and 385 are provided for operating the corresponding mechanism on the sliding frame 300 from the main drive shaft 111.

Rotation of the carrier frame 375 around the gear 372 produces a constant rotation of the bevelled pinions 373. Fixed to these pinions 373 are large gears 386 which mesh with gear members 387, mounted to rotate freely upon stub shafts 388, carried by the frame 375. Each of the gears 387 has an axial extension or hub 389 carrying a series of wrapper-engaging rod or finger members 390. These rod elements 390 are connected to flanges 391 on said hubs 389 by means of ball and socket joints 392, so that the rods are capable of universal movement within the sockets. They all extend transversely to the axis of rotation of the carrier 375; and the rods 390 on each of the gear members 387 extend toward the

other gear 387, the fingers in each of these groups being of such length that they overlap substantially as shown in Figs. 34 and 35. To hold the fingers 390 normally in a certain position, the extensions 389 are provided with a series of radial arms 393 projecting therefrom intermediate the fingers, and from these arms extend springs 394, which are connected to the fingers at 395. (Fig. 36.) This mounting of the rod members 390 makes them resiliently yielding in every direction with reference to the members 387.

The frame 375 has its opposite side members 396 and 397 so shaped that the group 80 of fingers carried by one of the gear members 387 is offset with respect to the group carried by the other gear 387, and the two groups overlap to a suitable extent the axial center line of the shaft 370, as clearly 85 indicated in Figs. 35 and 36.

During the operation of the machine, the two groups of fingers carried by the frame 297 and the two groups carried by the frame 300 move toward and away from each other 90 at regular intervals, being moved away from each other to permit cigars to be brought into position to be acted upon by the fingers, and being moved toward each other to act upon the cigars. Since the frames 375 are continually rotating so as to carry the groups of fingers around the cigar, and since the groups of fingers are themselves rotating about the stub shafts 388, the fingers strike the cigars from all sides and 95 operate to press down or iron and smooth the wrapping material to a snug fit upon the cigar surface where the material is creased about the tapering end of the cigar. After striking the cigar, each finger 100 continues to exert a pressure against the wrapping material as the finger moves or drags itself outwardly toward the end of the cigar, the springs 394 meanwhile allowing the fingers 105 to accommodate themselves gently to the contour of the cigar and preventing any injury thereto. (See Fig. 18.)

The fingers 390 may be of any suitable material, but their active portions preferably consist of short sections of wooden 115 rod or of polished metallic rod or tubing.

Carried by or forming a part of each of the frames 375 is a gear 398 (Figs. 18, 34 and 35) which meshes continually with the gears 362 and so drives the gatherers at 120 5, as already mentioned.

After a cigar has been received from the carrying device 216, the fourth step movement of the gripper device 257 carries the cigar into position to be operated upon by 125 the mechanism at 7. (See Figs. 1, 17 and 37 to 41.) It consists of elements for at once trimming off any excess or surplus wrapping material at the ends of the cigar, and for compacting, pressing and rounding to a 130

symmetrical form and to a smooth and attractive surface the portions of the wrapping material at and adjacent to the ends of the cigar.

5 One of these trimming and forming devices (illustrated in Figs. 37 and 38) is carried by and movable with the frame 297; the other (illustrated in Figs. 39, 40 and 41), which is of a somewhat different construction, is carried by the frame 300.

The trimming and forming device carried by the frame 297 consists of a thimble 399 whose interior is shaped to conform to the intended contour for the outer surface of 15 the mouth end of the cigar and has a smooth, polished surface. In the bottom of this thimble 399 are a plurality of slits 400 which serve as knives to engage and to cut off from the cigar any excess portions of 20 the wrapping material, i. e., portions which protrude objectionably. This trimming and forming thimble is substantially the same as shown and described in my pending application Serial No. 357,986, filed February 25 1920. The thimble 399 is carried in a cup member 401 mounted at the end of a rod 402. The cup member 401 has in its side walls openings 403, through which any 30 cuttings made by the knives 400 may be freely discharged. The thimble is removably held in position within the cup, as for instance, by means of retaining screws 403, so that it may be taken out for sharpening or the like, or replaced by a new thimble, 35 at will.

The rod 402 extends into a hollow shaft 404, which is rotatably mounted in one or more suitable bearings, as 405, carried by the frame 297. A collar 406, fixed to the 40 rod 402 within the shaft 404, has radial pins 407 which project through slots 408 in the shaft, so that the rod (and consequently the thimble 399) is caused to rotate with the shaft. Surrounding the rod 45 402 within the shaft 404 is a compression spring 409 which is interposed between the collar 406 and a ring 404^a that has press fit engagement with the shaft 404, and continually urges the thimble outwardly from 50 the shaft. The shaft 404 and the thimble 399 are rotated by a gear 410 on the shaft, which meshes with the gear 398 of the adjacent kneading device at 6. The gear 410 and a collar 411, also fixed on the shaft 55 404, engage one of the bearings 405 and prevent longitudinal movement of the shaft 404 relative to the frame 297.

The trimming and forming device carried by the frame 300 is intended for operating upon the fire end of the cigar. It consists (see Figs. 39, 40 and 41) of a flat trimming plate or cutter 412, which is carried by a head 413, which is in turn mounted upon a rod 414, slidable within a rotating hollow 60 shaft 415. This shaft 414, its drive, and the

connection of the rod 414 therewith may be substantially the same as just described with respect to the rod 402. The trimming plate 412 is arranged transversely to the axis of the shaft 415, and the central portion thereof, which engages against the end surface of the cigar, has therein a plurality of slits 416 whose edges serve as cutters for engaging and cutting off any portions of the wrapping material which project objectionably beyond the end of the cigar. 70

Also carried by the head 413 is a pair of arms 417, which are pivotally connected with the head at points 418 back of the trimming plate and have curved ironing members 419 at their forward ends in front of the trimming plate. As shown, the arms 417 carry yoke members 420, 423, respectively, which extend loosely around and beyond the other arm 417, and coil springs 421 interposed between each arm and the underlying portion of the head 413 act to urge the members 419 toward one another. Loosely pivoted rods 422 may be provided for retaining the 80 springs 421 in position. 90

The opposing surfaces of the compacting, forming and smoothing members 419 are preferably polished. As these members move on to the end of a cigar, they spread apart to accommodate the cigar and allow the flat end of the cigar to come into engagement with the trimming plate. When a cigar is brought into position by one of the grippers 257 to be operated upon by these trimming and forming devices, the frames 297 and 300 100 are separated, and the two trimming and forming devices are pressed outwardly to their fullest extent by their springs 409. After the cigar has taken its appointed position, the frames 297 and 300 move toward each other and bring the rotating trimmers and formers against the opposite ends of the cigar, the frames continuing to move for a slight distance after the devices have come to a fixed position endwise as a result of 105 engaging with the cigar. The trimming and forming devices are thus held by spring pressure against opposite ends of the cigar, so that as they rotate around the cigar they quickly and successfully perform their trimming, compacting, forming and smoothing functions—the latter especially at the edges of the cigar end. Their curvature and their 110 pivotal mounting and spring actuation enable them to adapt themselves properly to any shape of the fire end of a cigar whether 115 of large size or small. 120

After the trimming and ironing operations have been completed, and the frames 297 and 300 have moved apart, the next step 125 movement of the gripper carrying the cigar will bring the gripper into discharging position, in alignment with the slide bar 272 (Figs. 1 and 21) so that the extension 288 of the gripper will be engaged by the h 130

shaped end 289 of said slide bar at the next operation of the mechanism. Movement of the slide bar backwardly toward the shaft 259 will open the jaws of the gripper and allow the finished cigar to fall by gravity on the table 278, or into an appropriate receptacle place thereon to receive it.

What I claim is:

1. A method of wrapping a cigar, which 10 comprises rolling a wrapper about the cigar, creasing the wrapper about the tapering ends of the cigar, compacting the extreme ends of the wrapper on the cigar, pressing and smoothing the creased portions of the wrapper upon the cigar, and trimming off any excess of wrapping material at the ends.

2. A method of wrapping a cigar, which 20 comprises rolling a wrapper about the cigar, creasing the wrapper lengthwise about the tapering ends of the cigar, and pressing and smoothing the creased portions, and compacting the extreme ends of the wrapper on the cigar ends.

3. A method of perfecting a cigar wrapping, which comprises creasing the wrapper lengthwise of the cigar into a plurality of longitudinal creases, and pressing and smoothing the creased portions lengthwise to a close fit on the cigar.

30 4. The step in perfecting a cigar wrapping which consists in ironing and smoothing the wrapper lengthwise of the cigar to a snug conformity to the contour of its tapering ends.

35 5. A cigar-wrapping and sealing machine comprising, in combination, means for initially wrapping cigars in wrappers and applying a sealing agent, and means for feeding the cigars to said wrapping and sealing means, means for initially shaping the wrappers about the ends of the cigars, means for compacting the extreme ends of the wrappers, means for pressing down and smoothing the wrappers about the cigars, means 40 for trimming any excess of wrapping material at the ends of the cigar and finally smoothing the adjacent portions of the wrappers, and means for receiving the wrapped cigars from the initial wrapping means and successively presenting them to be operated on by the aforementioned means for perfecting the wrapping and sealing.

45 6. A cigar-wrapping machine comprising, in combination, a hopper and chute device 55 for receiving and feeding the cigars, relatively movable wrapping members receiving the cigars between them from the aforesaid feeding device and co-acting to roll them into a wrapper, means for perfecting the wrapping of the cigars in a plurality of successive operations at a plurality of successive stations, and means for receiving the initially wrapped cigars, holding them by the middle, and presenting them to be op-

erated on at said perfecting stations successively.

7. A cigar-wrapping machine comprising, in combination, a hopper and chute device for receiving and feeding the cigars, relatively oscillating wrapping members receiving the cigars between them from said chute device and co-acting to roll them downwardly into wrappers, means for perfecting the wrapping of the cigars in a plurality of successive operations at a plurality of successive stations, means for holding the cigars at the middle and presenting them to be operated on at said perfecting stations successively, means for separating said wrapping members after a rolling operation to release the cigar just rolled, and means for receiving the cigar so released and transferring it to the aforesaid holding means for perfecting.

8. Cigar-wrapping mechanism comprising, in combination, inclined relatively oscillating wrapping members co-acting to roll cigars downward between them into wrappers, one of said members having at its lower edge a cradle for receiving cigars 90 when said member is in its uppermost position, means for perfecting the wrapping of the cigars, means for separating said wrapping members when one of them is in its lowermost position to release the cigar just 95 rolled, and means for receiving the cigar so released from the aforesaid cradle and transferring it to said perfecting mechanism.

9. Cigar-wrapping mechanism comprising, in combination, relatively oscillating 100 wrapping members co-acting to roll cigars between them into wrappers, means for perfecting the wrapping of the cigars, means for separating said wrapping members after a rolling operation to release the cigar just 105 rolled, and means for taking the cigar so released and transferring it to said perfecting means.

10. A cigar-wrapping machine comprising, in combination, means for receiving and 110 feeding the cigars, wrapping means receiving the cigars from said feeding means acting to roll them into a wrapper, means for performing a plurality of further wrapping operations upon the cigars at a plurality of successive concentric stations, a carrier rotatable about an axis concentric with said stations having means for holding cigars by the middle to present their ends to be operated on at said stations, and means for 115 rotating said carrier step by step to advance the cigars from station to station with a dwell at each.

11. Cigar-wrapping mechanism comprising, in combination, relatively movable inclined wrapping plates, the lower one having a cigar-receiving cradle at its lower edge, means for feeding wrapping material

- across the lower plates into said cradle, means for serving a portion of said material including that in the cradle, means for dropping a cigar on the wrapping material 5 in the cradle, means for bringing such cigar to a definite lengthwise position thereon, means for turning in the leading edge of the wrapper on the cigar, means for applying adhesive to the wrapping material to hold 10 its outer edge when rolled about the cigar, and means for oscillating said plates relatively to one another to roll the wrapper about the cigar during the downward movement of the lower plate.
15. Cigar-wrapping mechanism comprising, in combination, relatively movable wrapping plates, one with a cigar-receiving cradle at one edge, means for periodically feeding wrapping material across said plate 20 to be received in said cradle, means for periodically severing the wrapping material fed to said cradle, means for periodically feeding cigars upon the wrapping material in said cradle, means for oscillating said 25 plates relatively to one another to roll a wrapper about a cigar, and means for turning in the leading edge of the wrappers on the cigars.
13. Cigar-wrapping mechanism comprising, in combination, relatively oscillating wrapping plates, means for periodically feeding wrapping material upon one of said plates, and means for periodically feeding cigars between said plates to be rolled in said 30 wrapping material by the relative movement of said plates.
14. Cigar-wrapping mechanism comprising in combination, a wrapping plate with a cigar-receiving cradle, means for feeding 40 wrapping material to said cradle, means for feeding cigars upon the wrapping material in said cradle, and means for bringing such cigars to a definite lengthwise position on said wrapping material.
45. Cigar-wrapping mechanism comprising, in combination, a wrapping plate with a cigar-receiving cradle, means for feeding cigars to said cradle, and means for engaging the ends of the cigars and bringing 50 them to a definite lengthwise position in said cradle.
16. Cigar-wrapping mechanism comprising, in combination, a wrapping plate with a cigar-receiving cradle, means for feeding 55 cigars to said cradle, and means for engaging the cigars and bringing them to a definite lengthwise position in said cradle, said means being resiliently yielding to obviate injury of long cigars.
60. Cigar-wrapping mechanism comprising, in combination, a wrapping plate with a cigar-receiving cradle, a plunger, and means for projecting it inwardly from one 65 end of said cradle to a definite position lengthwise thereof and there maintaining it as an abutment for one end of a cigar therein, and another plunger, with means for projecting it inwardly from the other end of said cradle to push the cigar endwise against the abutment afforded by said 70 first-mentioned plunger.
18. Cigar-wrapping mechanism comprising, in combination, a wrapping plate with a cigar-receiving cradle, means for dropping cigars sidewise into said cradle, and plungers for pushing on opposite ends of said 75 cigars when they have reached a position of rest in said cradle to bring them to definite lengthwise position in said cradle.
19. In combination of a wrapping plate 80 with a cigar-receiving cradle at one edge, a platen and means for periodically feeding wrapping material across it to said cradle, means for periodically holding said wrapping material fast, and means for applying adhesive to said wrapping material and severing a portion thereof while said material is held fast.
20. The combination of a wrapping plate, a platen and means for periodically feeding 85 wrapping material across it on to said wrapping plate, means extending transversely of said wrapping material for periodically holding it fast on said platen, a cutter with means for reciprocating it 90 across said material to sever the same, and means for adjusting said cutter longitudinally of said platen.
21. The combination of a wrapping plate and means for feeding wrapping material 100 across it, an adhesive container fixedly mounted adjacent to the plate, means for periodically conveying adhesive from the container to the said wrapping material, and means for holding the wrapping material fast to prevent it from pulling away 105 from the plate, controlled by said depositing means.
22. The combination of a wrapping plate and means for feeding wrapping material 110 across it, a stationary source of supply of liquid adhesive near said plate, an oscillatory carrying device for taking up adhesive from said supply and depositing it on said wrapping material, and means for holding the wrapping material fast on the plate actuated by said carrying device as it swings against said wrapping material.
23. The combination of a wrapping plate and means for feeding wrapping material 115 across it, a source of supply of liquid adhesive near said plate, an oscillatory carrying device for taking up adhesive from said supply and depositing it on said wrapping material, and means for turning said carrying device about a longitudinal axis as it swings over upon said wrapping material.
24. Cigar-wrapping mechanism comprising, in combination, an oscillatory wrapping plate with a cigar-receiving cradle at its 120

lower edge, a supply of wrapping material above said plate, and means for feeding the wrapping material downward from said supply roll on to said wrapping plate at 5 each downward movement of the latter.

25. The combination of a wrapping plate with a movable cigar-receiving cradle at its lower edge, a supply roll of fragile wrapping material above said plate, and means 10 for feeding wrapping material from said roll downwardly across said plate to said cradle comprising a feeder strip wound on said roll with said wrapping material, and means operable by the said cradle for pulling 15 on said feed strip and thereby unwinding said wrapping material from said roll.

26. The combination of a supply roll of fragile wrapping material, a feeder strip wound on said roll with said wrapping material, a movable wrapping plate for an 20 article to be wrapped and means operable by a movement of the said plate for pulling on said feed strip and thereby unwinding said wrapping material from said roll.

25. 27. The combination of a supply roll of fragile wrapping material, a feeder strip wound on said roll with said wrapping material, a movable wrapping plate for an 30 article to be wrapped and means actuated by the plate for periodically holding said feed strip fast at a point remote from said spool and pressing against it at an intermediate point, so as to draw said feed strip from said roll and thereby unwind the 35 wrapping material therefrom.

28. Cigar-wrapping mechanism comprising, in combination, a movable carrier with means for holding cigars, at their middle portions and means at successive stations 40 for performing successive wrapping and smoothing operations upon the projecting portions of cigars successively presented at said stations by said carrier.

29. Cigar-wrapping mechanism comprising, in combination, a movable carrier with 45 means for holding cigars by the middle portion thereof, frames at opposite sides of the path of movement of said carrier movable toward and away from the same, and means carried by said frames for engaging the cigars adjacent to their middle portions for performing successive wrapping and 50 smoothing operations concurrently on both ends of cigars successively presented thereto by said carrier.

30. Cigar-wrapping mechanism comprising, in combination, a carrier with means for holding cigars by the middle, means at successive stations for performing successive 60 wrapping operations upon both ends of cigars as presented at said stations by said carrier, and means for advancing said wrapping means into operation upon the projecting portions of such cigars and for retract-

ing the same to permit movement of the 65 cigars by the carrier.

31. Cigar-wrapping mechanism comprising, in combination, means for performing successive wrapping operations upon both 70 ends of a cigar concurrently at a plurality of successive stations, a carrier rotatable about an axis concentric with said stations having means for holding cigars by the middle to present their longitudinally tapering portions to be operated on at said stations, 75 and means for rotating said carrier step by step to advance the cigars from station to station with a dwell at each.

32. Cigar-wrapping mechanism comprising, in combination, a movable carrier provided with means for holding initially wrapped cigars, and means at successive stations for creasing the wrappers about the 80 ends of the cigars, for pressing and smoothing the creased portions of the wrappers 85 about the cigar ends, and for trimming off any excess of wrapping material at the ends of the cigars, the said means all being automatically operable in predetermined relation 90 with respect to the movements of the said carrier and connected thereto.

33. Cigar-wrapping mechanism comprising, in combination, a movable carrier with means for holding initially wrapped cigars by the middle, means at successive stations 95 on both sides of the path of movement of the carrier for creasing the wrappers lengthwise about the ends of the cigars, for compacting the extreme ends of the wrappers, and for pressing and smoothing the 100 creased portions of the wrappers about the cigar ends, and means controlled by movements of the carrier for concurrently advancing the aforesaid wrapper-perfecting 105 means into operation on opposite ends of the cigars and retracting the same.

34. Cigar-wrapping mechanism comprising a movable carrier with means for holding partially wrapped cigars by the middle, devices with convergently and expansively 110 movable elements for engaging the wrapper on the two ends of such a cigar so held, means for concurrently advancing said devices upon the cigar and retracting them, 115 and means for bringing said elements together upon the cigar after their advance for retraction in contact with the wrapper.

35. Cigar-wrapping mechanism comprising, in combination, means for holding partially wrapped cigars, a device with elements for engaging the wrapper convergently and expansively movable, means for advancing said device upon the cigar with 120 said elements apart, means for bringing said elements together, and means for retracting said device with said elements in contact with the wrapper.

36. Cigar-wrapping mechanism compris-

- ing a device with convergently and expansively movable elements for engaging the wrapper on a cigar movable to advance upon a cigar and to be withdrawn therefrom, 5 means shiftable lengthwise of said device for controlling the expansion and convergence of said elements, and means controlled by the movement of said device as aforesaid for actuating said means to keep said elements apart during the advance on a cigar and together during its retraction.
37. A cigar-wrapping device comprising a longitudinally movable member, a plurality of convergently and expansively movable 15 spring-actuated fingers pivoted thereon and carrying means for engaging the wrapper on a cigar at their forward ends, and a member shiftable lengthwise of said longitudinally movable member to control the expansion and convergence of said fingers.
38. A cigar-wrapping device comprising a longitudinally movable member, a plurality of convergently and expansively movable spring-actuated fingers pivoted thereon and 25 carrying means for engaging the wrapper on a cigar at their forward ends, and other spring-actuated fingers pivoted and movable as aforesaid having at their forward ends a flexible loop and adapted to draw the same 30 taut about and along the cigar.
39. A cigar-wrapping device adapted to be advanced upon a partially wrapped cigar and retracted, said device comprising a plurality of elements adapted to bear upon the 35 wrapper and crease the same lengthwise of the cigar during retraction of the device, and a flexible loop with means for drawing it taut about and along the cigar after said elements to smooth down the outstanding 40 creases formed by them as aforesaid.
40. A cigar-wrapping device adapted to be advanced upon a partially wrapped cigar and retracted, said device comprising a flexible loop adapted to surround the cigar wrap- 45 per, and means for drawing the loop taut about and along the wrapper during retrac- tion of said device.
41. A cigar-wrapping device adapted to be advanced upon a cigar and retracted, said 50 device comprising a plurality of spring-actuated fingers each with members at its forward end adapted to extend to opposite sides of a cigar operated on by the device, flexible cords connecting said member on 55 each spring finger, and means for supporting the bights of said flexible cords to form an open loop for encircling the cigar.
42. A cigar-wrapping device adapted to be advanced upon a wrapper for a cigar 60 and retracted, said device comprising a pair of relatively movable jaws with registering longitudinal grooves for receiving the end of the cigar-wrapping, and means controlled by the advance and retraction of said device 65 for closing and opening said jaws.
43. A cigar-wrapping device comprising a rotating carrier, and wrapper-engaging means on said carrier rotating about an axis transverse to the axis of rotation of the carrier for pressing and smoothing the 70 wrapper about the cigar.
44. A cigar-wrapping device comprising a rotating carrier, and a plurality of rods on said carrier extending transversely to the carrier axis and also revolving about an axis 75 transverse thereto.
45. A cigar-wrapping device comprising a rotating carrier, and an ironer thereon rotating about an axis transverse to the axis of rotation of the carrier and comprising a 80 plurality of yielding cigar-ironing members.
46. A cigar-wrapping device comprising a rotating carrier, a member mounted thereon for rotation about an axis transverse to that of said carrier, and a plurality of 85 rods on said member resiliently yielding with reference thereto in every direction and extending transversely of the axis of rotation of the carrier.
47. A rotary cigar-wrapper trimming and 90 forming device comprising a cutter extending transverse to the axis of rotation, and jaws in front of said cutter movable transversely to the axis of rotation and yieldingly pressed together so as to engage and smooth a cigar 95 wrapper while any excess at the end of the cigar is trimmed off by said cutter.
48. A rotary cigar-wrapper trimming and 100 forming device comprising a cutter extending transverse to the axis of rotation, and divergent-faced jaws movable across the front of said cutter to engage and smooth a cigar wrapper adjacent the end of a cigar.
49. A rotary cigar-wrapper trimming and 105 forming device comprising a cutter extending transverse to the axis of rotation, and jaws pivoted about axes transverse to the aforesaid axis of rotation behind said cutter having outwardly-curved divergent faces, and yieldingly pressed together to engage 110 and smooth a cigar-wrapper adjacent the end of the cigar.
50. Cigar-wrapping mechanism comprising a rotary carrier with gripping jaws biased to close and grip a cigar, and means 115 including a crank device co-axial with said carrier for opening said jaws in their receiving and discharging positions.
51. A gripping device for cigar wrapping comprising a carrier arm, and gripping jaws 120 thereon relatively movable lengthwise thereof and resiliently biased toward closing.
52. A gripping device for cigar wrapping comprising a carrier arm, gripping jaws 125 thereon relatively movable lengthwise thereof to grip or release a cigar extending transversely of said arm, and a spring urging said jaws together.
53. A gripping device for cigar wrapping 130

- comprising a carrier arm, a pair of gripping jaws constrained to move in unison toward or away from one another lengthwise of said arm, an abutment movable lengthwise of said arm with one of said jaws, and a compression spring between said abutment and another abutment on said arm urging said jaws together. 5
54. The combination in wrapping mechanism, of a supply roll of wrapping material, a feeder strip wound on said roll, wrapping mechanism and means controlled by the movements of said mechanism for unwinding the feeder strip. 10
55. The combination in wrapping mechanism, of a supply roll of wrapping material, a feeder strip wound on said roll, a wrapping plate, means for grasping an unwound portion of the feeder strip, an oscillating member mounted for movement into engagement with the feeder strip at a point intermediate said grasping means and the roll, and means controlled by movements of the wrapping plate for operating said grasping and oscillating members. 20
56. The combination in wrapping mechanism, of a supply roll of wrapping material, 25
- a feeder strip by means of which the roll may be unwound, wrapping mechanism for utilizing said material, and means operable in synchronism with the wrapping mechanism for actuating the feeder strip. 30
57. Mechanism for wrapping cigars, comprising means for applying adhesive to a sheet of wrapping material, a reciprocably movable wrapping plate, means for depositing the sheet on said plate, means for depositing a cigar on said sheet, and means cooperating with said plate when moving in one direction to cause said wrapper to encircle the cigar. 35
58. Mechanism for wrapping cigars, comprising a reciprocably movable wrapping plate, means for depositing a sheet of wrapping material on said plate, means for depositing a cigar on said sheet, and means cooperating with said plate when moving in one direction to cause said wrapper to encircle the cigar. 40
- In testimony whereof I have hereunto affixed my signature this 23rd day of March, 1921. 45

ALBERT E. MASPONS.
